UNITED STATES PATENT OFFICE.

OTTO FILMAN HAMMILL, OF CALGARY, ALBERTA, CANADA.

SHEAF SHOCKER.

Application filed January 25, 1922. Serial No. 531,784.

To all whom it may concern:

Be it known that I, OTTO FILMAN HAMMILL, of the city of Calgary, in the Province of Alberta and Dominion of Canada, a subject of the King of Great Britain, have invented certain new and useful Improvements in Sheaf Shockers, of which the following is a specification.

This application is a continuation, in part, 10 of my application, Serial No. 472,785 filed May 26, 1921.

This invention relates to improvements in sheaf shockers, and the objects of the invention are to provide an effective device of this 15 character which will receive the sheaves from the binder, form them into properly compressed and shaped shocks and deposit them in upright position on the ground.

More particular objects of the invention 20 are to effect proper compression of the upper part of the shock and spreading of the lower part thereof during discharge in order that the shock when deposited may have a maximum amount of stability.

The invention relates to a type of shocker 25 in which the sheaves are deposited into a shock forming member or basket and by this member formed into a shock and deposited on to the ground.

Further objects of the invention relate to 30 an improvement in a shock forming member to enable it to receive the sheaves at one side and discharge them at the other, thereby avoiding the necessity of lifting the basket from the shock when placed.

Further objects still relate to the tripping and operating mechanism for the basket, the latter being thrown into operation by the 40 initial movement of the basket under gravity and designed to complete the operation of the basket and return it to normal position.

Further objects still are to essentially improve and simplify the construction of the 45 device to better adapt the various parts to perform the functions required of them.

In its construction, the invention includes 50 a shock forming member and basket formed in two co-operating parts mounted on tracks designed to cause the basket to open alternately on opposite sides to receive and discharge the sheaves in combination with a baseboard and spreading means, and power

operating mechanism by which the various parts are operated in proper sequence, all as 55 hereinafter more fully set forth and described in the accompanying specification and drawings.

In the drawings:

Figure 1 is a side elevation of an embodiment of the invention.

Figure 2 is a front elevation.

Figure 3 is a plan view.

Figure 4 is a perspective detail of one part 65 of the basket or shock forming member.

Figure 5 is a sectional detail through the supporting means for the one section of the basket.

Figure 6 is a perspective detail of one of 70 the connecting arms for the section of the shock forming basket.

Figure 7 is a perspective detail of the supporting bracket on one section of the shock forming basket.

Figure 8 is an end view of the bracket 75 shown in Figure 6.

Figure 9 is a perspective detail of the trip controlling device.

Figure 10 is a perspective detail of the 80 cam plates on the trip device.

Figure 11 is a side elevation of the trip control mechanism and clutch.

Figure 12 is a plan view of the trip control mechanism and clutch.

Figure 13 is a sectional detail showing the 85 connection between the bracket and frame shown in Figures 6 and 7.

Figure 14 is a detail and sectional elevation of one of the supporting wheels of the basket.

Figure 15 is a perspective detail of a portion 90 of the controlling mechanism for the basket.

Figure 16 is a perspective detail of a portion of the controlling cables for the basket.

Figure 17 is a plan view of the cable as 95 shown in Figure 16.

Figure 18 is a sectional detail showing a portion of the elevator mechanism.

Figure 19 is a side view of a portion of 100 the elevating mechanism.

Figure 20 is a detail in plan of the driving mechanism for the elevator.

Figure 21 is a sectional detail of the supporting means for the rod 46.

In the drawings, like characters of refer-

ence indicate corresponding parts in all the figures.

Referring to the drawings:

A indicates a shock forming member or basket carried on a suitable truck B and fed with sheaves by a suitable elevator C operating from the binder deck D. The truck B may be of any suitable or convenient design to support the working parts, that illustrated having side wheels 10 and a castor wheel 11, the truck carrying a suitable frame E of suitable shape and design to properly support the various operating parts.

The elevator C may be of any suitable or convenient design. I have illustrated a well known type comprising endless chains 12 carrying transversely extending and pivoted forks 13 which are maintained in upright position by means of projections 14 which engage with flanges 15 on the side of the elevator casing 16. (See Figure 19.)

The elevator is driven in a suitable or convenient way. I have shown it driven by means of a chain 17 leading from a sprocket 18 on a countershaft 19 connected by a gearing 20 with a sprocket 21 driven by a chain 22 from a sprocket 23 on the shaft 24 of one of the wheels 10. While the sheaves are passing up the elevator and discharging into the shock forming member they are guided by suitable guide rails 24¹ which extend parallel with the elevator and are supported on a transverse member 25 of the frame, the latter being of inverted U shape designed to guide and cause discharge of the sheaves into substantially the centre of the shock forming member. The connection between the guide rails 24¹ and the transversely extending member 25 is constituted by a rod 27 (see Figure 3), the outer end of which is connected by a bracket 28 to the side of the elevator casing 16. The rod 27 is also provided with vertical fingers 26.

The shock forming member or basket C is formed with two semi-circular and similar sections 30 each mounted at opposite sides on guide tracks F by which the movement of each section is controlled, the shape of the tracks being such as to cause the sections to close together, to turn downwardly and open rearwardly to compress and discharge the sheaves in the form of a shock as hereinafter explained. It will be seen that each pair of tracks F comprises an upper rail 31 and a lower rail 32. The central portions of all the rails extend parallel with each other for a distance, then the rails of each pair diverge from those of the other pair at the rear as shown in Figure 3. They also curve upwardly, outwardly and backwardly at the forward end. (See Figures 1 and 2.) One rail of each pair also curves outwardly at the forward end to cause expansion of the top as well as opening the

basket to receive the sheaves. On the discharge, the contraction or movement of the top portions towards each other will compress the top of the sheaves.

The connection between each section of the basket and its respective track may be of any convenient character which will allow free and easy motion of the section on the track, and is preferably formed with rollers or balls to reduce any unnecessary friction. 70 In the form of connection which I have shown, a bracket 33 is provided connected to each section 30 and designed to fit within a flange 34 formed around a rectangular frame 35 to which it is adjustably connected, as by bolts 36 extending through corresponding perforations in the bracket and frame, a series of perforations being provided in each to provide for adjustment between them to correspond with different lengths of grain. The frame 35 has sockets 37 secured to the side thereof which form bearings for pivot pins 38 retained in the sockets by means of threaded extensions 39 extending through the ends of the sockets and having retaining nuts 40 thereon. The outer end of each pin 39 is formed with diverging arms 41 and 42 which carry friction rollers 43 adapted to run on the upper rail 31, a third friction roller being mounted at the end of the pin 38 centrally between the arms 41 and 42.

The lower rail is engaged by a plurality of corresponding rollers 44 mounted in arms 45 on the rod 46 which is mounted in bearings 47 and 48 on the frame 35. 100

Each of the sections 30 is curved, being partially conical in shape and is formed with spaced forks 50 having the ends at both sides designed to overlap the opposite section according to which side of the basket is open. The lower sides of the sections are also formed with overlapping projections 51 designed to secure registration of the sections when brought together and hold them in proper alignment when separated slightly. 110

The sections of the basket tend to move by gravity on the tracks to discharge position and their motion in this direction is normally prevented by means of a pivoted trip 52 pivoted on a member 25 and normally spring held in engaged position by a spring 53, being released by means of a cord 54 which extends over a suitable pulley or pulleys 55 to a position adjacent to the driver's seat. The trip is formed with a laterally turned end which normally engages a stop 56 on the side of a trip gear wheel 57 (see Figures 9, 10 and 11) mounted on a stub shaft 58 and meshing with a pinion 59 carried on a countershaft 60 which countershaft is provided with spirally curved pulleys 61 having cables 62 which lead over suitable pulleys 63 to the sides of 120 125 130

the sections of the shock forming basket A. Springs 62^a may be interposed between the cables and sections 30 to absorb shock. It will be seen that when the trip is in normal position, the gear 57 can not move, which will prevent turning of the pinion 59 and the shaft 60 which through the pulley 61 and cable 62 will retain the sections in their raised and expanded position.

Upon release of the trip 52, the sections 30 will commence to move downwardly on the tracks under gravity, and in so doing they are designed to throw into operation the power operating means presently to be described.

The trip gear 57 carries cam plates 64 and 65, the cam plate 64 extending around three-quarters of the periphery of the gear 20 and the cam plate 65 extending between the ends of the cam plate 64 as shown in Figures 9, 10, 11 and 12. As the trip 52 is released, the gear 57 commences to turn, being driven from the pinion 59 which is turned by the shaft 60 which is itself turned by the weight 25 of the sections 30 acting through the cables 62. The turned end 66 on the cam 64 is designed to engage a roller 67 on a slidably mounted operating rod 68 and move the same in the direction indicated by the arrow 30 in Figure 12. The outer end of the rod 68 is connected to a centrally fulcrumed clutch control lever 69 pivoted to a bracket 70 and connected to a clutch block 71 adapted 35 to rotate with the shaft 60 but slidably mounted thereon the said block having pins 72 on one side designed to enter suitable orifices in the hub of a bevel gear 73 during discharge of the shock forming basket, and 40 formed on the opposite side with pins 74 designed to enter suitable recesses in a bevel gear 75 on the return movement of the basket. In neutral position, the pins 72 and 74 will be free from either gear. The gears 45 are caused to rotate in reverse direction to each other by a connecting gear 76 suitably mounted on the bracket 77 connected to the member 25. The gear 73 is connected to and driven continuously from a sprocket 78 50 which is connected by a chain 79 with a corresponding sprocket 80 carried by and turning with one of the wheels 10. It will be seen that when the rod 68 is moved outwardly by engagement of the portion 66 of 55 the cam with the roller 67, the clutch block 71 will be moved to cause the pins 72 to engage in the recesses provided in the gear 73 which will cause the shaft 60 to be turned in what may be termed the forward direction 60 during which the shock forming apparatus will be moved to discharge position, this being accomplished by means of cables 80^a which extend from the brackets 35 on the sections 30 over suitable pulleys 81 to spirally grooved or worm winding pulleys or

drums 82 provided on the shaft 60. It will be seen that the tightening of these cables 80^a will draw the sections of the basket on the tracks to their rearmost or discharging position as shown in dotted lines in Figure 3, during which period the roller 67 will run on the intermediate flat portion 83 of the cam 64 finally reaching an end portion 84 which is beneath the curved portion 85 on the cam 65. The roller 67 will finally 75 pass off the end 84 and, under action of a spring 86 extending between the rod 68 and the bracket 70, will pass beyond the end of the portion 64. When the roller passes beyond the end of the portion 64 it will permit the rod 68 to be moved into reversed position under action of the spring 86, whereupon the pins 74 will engage with the gear 75 and the shaft 64 will be driven in the reverse direction. The reverse operation of the shaft will, through the cable 62, draw the basket back to its normal position during which movement the roller 68 will pass on the opposite side of the cam 64 to that on which it previously moved, and will finally reach the curved portion 87 on the cam 65. This curved portion will then move the roller 67 back to its normal position, the said roller springing under the end 66 on the cam 64, which end is split at 88 to 95 render it sufficiently resilient to permit of the passage of the roller beneath it, as indicated in dotted lines in Figure 9. During this movement, the clutch control lever 69 will be moved by the rod 68 to neutral 100 position causing the reverse movement of the shaft 60 to cease, at which time the trip rod 52 will have engaged with the stop block 56 retaining the parts in their normal position. 105

During formation of the shock, the butts of the sheaf are supported by a pivotally mounted baseboard G which is pivoted at its lower extremity to short links 90 pivoted to depending brackets 91 on the bottom 110 member 92 of the frame. These links permit the baseboard to be swung from its normal position shown in full lines in Figure 1 to its lower position shown in dotted lines in Figure 1, its movement being also controlled 115 by means of a link 93 which extends from the frame 92 to the side of the baseboard. The movement of the baseboard is controlled by a cable 94 which extends over the pulley 63 and is connected to the cable 62 by means 120 of a plate 95 through which the cable 62 extends, but which is adapted to be engaged by a knot or stop block 96 on the cable 62 (see Figures 16 and 17). The baseboard G is caused by gravity to move to lowermost 125 position and is arrested by the plate 95 engaging the stop block 96. During discharge, the movement of the cable 62 will permit the plate 95 to move and the cable 94 to lower the baseboard a given amount, 130

this movement being finally arrested by means of a stop bracket 97 on the frame which engages the plate 95, the bracket being provided with an eye 98 which permits 5 the knot 96 to pass through it but which arrests the movement of the plate 95. A spring 99 is interposed between the end of the cables 94 and the baseboard in order to lessen the jar and give a resilient support 10 to the baseboard in normal position. This resilient support is such that the baseboard when the shock forming member is empty is held in the position shown in full lines in Figure 1. It will be maintained in this position 15 during the discharge into the shock forming member of the first few sheaves. As the sheaves accumulate in the shock forming member, the spring will permit the baseboard to give a little and to move as indicated 20 in dotted lines in Figure 1 thereby giving greater accommodation for the base of the sheaves, thereby avoiding while the first few sheaves are collecting the opening of any wide space between the members 25 30 and the baseboard.

In order to cause spreading of a portion of the butts of the sheaves during discharge of the shock, diverging shoulders 100 and 101 are formed on the baseboard G. To 30 maintain or continue this spreading action, diverging forks 102 are provided at the end of the shoulders and project from the baseboard to the ground. (See Figures 1 and 2.)

To prevent discharging of the sheaves 35 from the binder into the shock forming member while the latter is discharging, a pivoted fork 103 is provided, mounted above the shock forming member on suitable brackets 104 designed normally to be free 40 to tilt downwardly under the weight of each sheaf, being returned to normal position by the weight of an arm 105, the downward movement of which is limited by a detent bracket 106. To prevent downward 45 swinging of the forks 103 and corresponding upward swinging of the arm 105 during discharge of the shock forming member, I provide a pivoted detent lever 107 pivoted to a suitable bracket 108. The detent lever 50 is formed with a hook-shaped end 109 designed to be brought across the end of the arm 105. The detent lever 107 is operated by means of a pivoted operating lever 110 pivoted to the member 111 of the frame. 55 Said detent lever is formed with a forked end 112 designed to be engaged by the plate 95 on the cable 62. When the plate 95 is removed from engagement with the forked end 112 during movement of the cable 62 in 60 the discharge of the shock forming member, the lever 110 will move under action of the spring 114 and operate the detent lever 107, as already explained. It will be seen, therefore, that until the plate 95 is returned to 65 normal position, which will take place when

the shock forming member itself is returned to normal position any tilting of the fork 103 is prevented by engagement of the detent lever 107 with the projecting end of the arm 105.

Suitable provision may be made for the adjustment of the height of the shock forming mechanism from the ground to suit varying crop conditions. The means which I have shown to accomplish this purpose 70 comprise an adjustable support for the wheels 10, comprising upwardly turned extinctions 120 on the supporting pins 121 of the wheels, the extensions being held in adjusted position in supporting brackets 122 by means of bolts 123 extending through the extensions 120 into one of the series of perforations 124 in the bracket. A similar adjustable support is also provided for the 75 castor wheel 11.

In the operation of the machine, the sheaves as they are discharged from the binder deck are caught by the fork 13 on the conveyor C and lifted, finally passing on to the fork 103 which permits them to 80 drop one by one into the shock forming member, being guided finally by the fingers 26. The upper sides of the sections 30 of the shock forming member will be open and expanded at the top as shown in full lines 85 in Figures 2 and 3.

It will be seen that owing to the tapered form and curved form of the sections, the sheaves will be caused to arrange themselves in a proper shock at the same time the machine is moving over the ground and the baseboard being resiliently supported will permit a slight shaking movement against the resilience of the spring, which will further cause proper formation of the shock. 90 When the driver has ascertained that there is a sufficient number of sheaves in the shock forming member to form a proper shock, he pulls the cable 54 to release the trip 52 which through the mechanism already described, will permit the sections of the shock forming member first to move under their own weight and then to be moved by the power mechanism to discharge position. The movement of the upper part of the 95 shock forming members towards each other will compress the upper part of the sheaves at the beginning of the operation. At the same time, the shock forming member will be moved from a position slightly inclined 100 to the horizontal to a substantially vertical position. The variation in the speed of the shock forming member with respect to the ground will cause the butts of the sheaves to be spread slightly upon the ground. The 105 butts of the remaining sheaves will in the meantime have been spread by engagement with the flanges 100 and 101 of the baseboard. In this way, an effective spreading 110 of the butts of the shock is provided for. 115 120 125 130

The shock forming members continuing to move rearwardly on the rails 31 and 32 will finally open at their rearward or stubbleward side, moving to the position shown 5 in dotted lines in Figure 3 and leaving the shock well set up in a stubbleward direction while the sections of the shock forming mechanism are returning to normal position by the mechanism the operation of 10 which has already been described.

It may be pointed out that after the shock is deposited on the ground, the pressure of the shock forming member on the upper part of the sheaves will by reason of its conical shape compress the same together into a firm and stable shock, after which the stubbleward side of the basket will open to permit the basket to be withdrawn and returned to its normal position in which it will be 20 raised and opened ready to receive the new sheaves.

It will be seen that the adjustment between the brackets 33 and the frame 35 enables the relative position of the sections 30 25 to be adjusted and by this means a variation may be made in the extent of the compression at the top of the shock. It will also be seen that the adjustment at this point will cause the sections to be opened to a greater 30 or less extent at the top of the upward movement.

It will be seen that by reason of the fact that the worm pulleys 61 and 82 are spirally formed a variation takes place in the 35 speed at which the cables are paid out or drawn in and this variation in speed is taken advantage of in order to cause the sections 30 of the shock forming member to move at different speeds during their discharge.

40 The initial movement of the sheaf forming basket from open and spread position takes place at a minimum speed. The speed then greatly increases until, when the first part of the shock drops onto the ground, the 45 sheaf forming basket is moving slower than the movement of the entire machine over the ground. The variation in speed of the shock forming basket with respect to the ground will then cause the butt of the sheaf to be 50 spread slightly upon the ground. By the time the remainder of the shock is dropped on the ground, the shock forming basket will remain temporarily with the shock, pressing it to form on the ground, and finally leaving it in such position. The balance 55 of the movement of the sections is then completed, the final movement taking place at reduced speed. It will be obvious that the speed of any part of the movement may be 60 regulated by the diameter of the groove on the controlling pulley for that part of its movement.

As many changes could be made in the 65 above construction and many widely different embodiments of my invention within

the scope of the claims, constructed without departing from the spirit or scope thereof, it is intended that all matter contained in the accompanying specification and drawings shall be interpreted as illustrative and 70 not in a limiting sense.

What I claim as my invention is:

1. In a shocker and in combination a shock forming member adapted to open on one side to receive the sheaves and to open 75 on the opposite side to discharge them, means for reciprocating the member as a whole with parallel motion backwardly and forwardly, raising it when moved forwardly, including means for operating the 80 shock forming member to cause it to receive, compress and discharge the sheaves.

2. In a shocker and in combination a shock forming basket formed in two sections adapted to overlap on either side and 85 designed to open on one side to receive the sheaves and to open on the other side to discharge them, means for reciprocating the member as a whole with parallel motion backwardly and forwardly, raising it when 90 moved forwardly and including means for operating the basket to cause it to receive, compress and discharge the sheaves.

3. In a shocker and in combination a shock forming member adapted to open on one side 95 to receive the sheaves and to open on the opposite side to discharge them, means for reciprocating the member as a whole with parallel motion backwardly and forwardly raising it when moved forwardly including 100 means for operating the shock forming member to cause it to receive, compress and discharge the sheaves and means for causing the shock forming member to compress the shock to a greater extent near the top 105 than near the bottom.

4. In a shocker and in combination a shock forming member adapted to open on one side to receive the sheaves and to open 110 on the opposite side to discharge them, means for operating the shock forming member to cause it to receive, compress and discharge the sheaves including guide tracks diverging from each other near the discharge point.

5. In a shocker and in combination a shock forming basket, supporting means for the basket adapted to support it in such a way that it tends to move by gravity towards discharging position, a trip device 115 normally restraining the movement of the shock forming member towards discharging position, means for releasing the trip and power means set in operation by movement of the shock forming mechanism for completing the movement thereof and returning the shock forming member to normal position.

6. In a shocker and in combination a shock forming basket formed in two co- 130

operating sections adapted to open on one side to receive the sheaves and to open on the opposite side to discharge them, means for supporting and operating the sections of the basket, a movable baseboard, means for moving the baseboard to correspond with the movement of the basket, a pair of links supporting the baseboard and a spring normally tending to return the baseboard to normal position adjacent to the end of the shock forming basket.

7. In a shocker and in combination a shock forming basket formed in two curved sections adapted to co-operate with each other to open on one side to receive the sheaves and on the opposite side to discharge them, two pairs of rails, connecting means between each pair of rails and one section of the basket whereby the section of the basket is movably supported on the rail, means for operating the sections of the basket to cause them to receive, compress and discharge the sheaves in the form of a shock, and curved overlapping arms formed on each of the sections of the basket.

8. In a shocker and in combination a shock forming basket formed in two co-operating curved sections, means for supporting the operating sections of the basket, a movable baseboard, means for moving the baseboard to correspond with the movement of the basket, the said means including a pulley and cable connection between the basket and baseboard.

35 9. In a shocker and in combination a shock forming member, supporting means for the member adapted to support it in such a way that it tends to move by gravity towards discharging position, a trip device normally restraining the movement of the shock forming member towards discharging position, means for releasing the trip and power means set in operation by movement of the shock forming member for completing the movement thereof and returning the shock forming member to normal position, including an automatic reversing clutch.

50 10. In a shocker and in combination a shock forming member, supporting means for the member adapted to support it in such a way that it tends to move by gravity towards discharging position, a trip device normally restraining the movement of the shock forming member towards discharging position, means for releasing the trip and power means set in operation by movement of the shock forming member for completing the movement thereof and returning the shock forming member to normal position, said releasing means including an automatic reversing clutch and hand operated disengaging means.

55 11. In a shocker and in combination a shock forming member formed in two sec-

tions, tracks supporting the sections, adjustable connecting means between the tracks and the sections permitting adjustment to correspond with grain of different length.

70 12. In a shocker and in combination a shock forming member formed in two sections, tracks supporting the sections, adjustable connecting means between the tracks and the sections permitting adjustment to correspond with grain of different length, the said last mentioned means comprising brackets secured to the sections and frames adjustably connected to the brackets having means slidably engaging the brackets.

75 13. In a shocker and in combination a shock forming member formed in two sections, tracks supporting the sections, adjustable connecting means between the tracks and the sections permitting adjustment to correspond with grain of different length, the said last mentioned means comprising brackets secured to the sections and frames adjustably connected to the brackets having means slidably engaging the tracks, including pivot pins and rollers carried by the pivot pins bearing on the tracks.

80 14. In a shocker of the character described, a shock forming basket including a plurality of sections, brackets on the sections, frames adjustably connected to the brackets, a plurality of rollers carried by the frame, guide tracks engaged by the rollers, and means for actuating the sections on the tracks.

85 15. In a shocker and in combination a shock forming basket formed in two curved sections adapted to co-operate with each other to open on one side to receive the sheaves and on the opposite side to discharge them, two pairs of rails, connecting means between each pair of rails and one section of the basket whereby the section of the basket is movably supported on the rails, means for operating the sections of the basket to cause them to receive, compress and discharge the sheaves in the form of a shock and overlapping projections formed on the sections.

90 16. In a shocker and in combination a shock forming basket formed in two curved sections adapted to co-operate with each other to open on one side to receive the sheaves and on the opposite side to discharge them, two pairs of rails, connecting means between each pair of rails and one section of the basket whereby the section of the basket is movably supported on the rails, means for operating the sections of the basket to cause them to receive, compress and discharge the sheaves in the form of a shock and spaced forks formed on each section designed to overlap the opposite section at each side.

- forming mechanism including a pair of sections adapted to open on one side to receive the sheaves and on the opposite side to discharge them, brackets supporting the sections, operating means for the sections including pulleys and cables connected to the sections, a baseboard, and means for moving the baseboard to correspond with the movement of the aforesaid sections, including 5 cable means connected to the baseboard and to the cables which operate the sections.
18. In a shocker and in combination shock forming mechanism including a pair of sections adapted to open on one side to receive the sheaves and on the opposite side to discharge them, brackets supporting the sections, operating means for the sections including pulleys and cables connected to the sections, a baseboard, and means for moving 10 the baseboard to correspond with the movement of the aforesaid sections, including cable means connected to the baseboard and to the cables which operate the sections, the said connection between the cables being 15 formed by a stop on one cable engaging a plate carried by the opposite cable and a bracket surrounding the one cable having an eye thereon through which the stop may pass but adapted to arrest the plate.
19. In a shocker and in combination a shock forming member adapted to open on one side to receive the sheaves and to open on the opposite side to discharge them, means for operating the shock forming member to cause it to receive, compress and discharge the sheaves, and elevating means adapted to receive each sheaf from the binder deck and elevate and discharge it in the shock forming basket, and means for preventing discharge of the sheaves from the elevating means to the shock forming member during discharge of the shock forming member, the said last mentioned means comprising a pivoted fork member and a pivoted detent 20 lever adapted to prevent operation of the fork member during discharge of the shock forming member.
20. In a shocker and in combination a shock forming member, elevating means designed to receive the sheaves from the binder deck and elevate the same, a pivoted fork member designed to receive the sheaves from the elevating mechanism and discharge them into the shock forming mechanism, and a pivoted curved arm connected to the fork 25 designed to maintain it in normal position and permitting it to swing downwardly to discharge the sheaves into the shock forming member, a pivoted detent adapted to engage the end of the arm, and a spring actuated lever connected to the detent, operating means for the shock forming member including a cable, a stop on the cable adapted to engage the spring actuated lever to cause it to operate the detent lever to prevent discharge of the sheaves from the forks during operation of the shock forming member.
21. A shock forming operating and reversing mechanism comprising a reversible clutch, a lever controlling the clutch, a partially circular cam having a curved end, a second cam having a curved portion extending beneath the curved end on the first mentioned cam, and a roller operatively connected to the clutch operating lever and designed to operate on both cams to cause the clutch to be first thrown in one direction, then to be reversed and then restored to normal position.
22. In a shocker, an automatic reversing mechanism comprising a partly circular cam having a curved spring end, a second cam having a curved portion extending beneath the said spring end and another curved portion extending above the opposite end, an operating rod having a roller adapted to operate on both sides of the first mentioned cam and a reversing clutch operatively connected to the operating rod.
23. In a shocker, an automatic reversing mechanism comprising a partly circular cam having a curved spring end, a second cam having a curved portion extending beneath the said spring end and another curved portion extending above the opposite end, an operating rod having a roller adapted to operate on both sides of the first mentioned cam and a reversing clutch operatively connected to the operating rod, a trip gear carrying a cam, a stop on the gear, and a pivoted spring actuated trip member adapted to engage the stop.
24. In a shocker and in combination a shock forming basket formed in two curved sections adapted to co-operate with each other to open on one side to receive the sheaves and on the opposite side to discharge them, two pairs of rails, connecting means between each pair of rails and one section of the basket whereby the section of the basket is movably supported on the rails means for operating the sections of the basket to cause them to receive, compress and discharge the sheaves in the form of a shock, including two sets of grooved pulleys, cables leading in opposite directions from the grooved pulleys to the sections and adapted to move them to discharge position and to normal position respectively, and pulleys supporting the aforesaid cables.
25. In a sheaf shocker and in combination a shock forming member formed in two sections, means for mounting the sections with freedom to reciprocate as a whole backwardly and forwardly and to separate from each other at the end of the backward and forward movement, operating means for the

sections including backward and forward guide cables, and means for operating the guide cables at different speed during different parts of the movement of the sections.

5 26. In a sheaf shocker and in combination, a reciprocable shock-forming member formed in two sections, actuating means for

the sections including a controlling cable, and means for moving the cable at varied speeds to correspond with the position of 10 the shock-forming member.

In witness whereof I have hereunto set my hand.

OTTO FILMAN HAMMILL.
